Attorney

UNITED STATES PATENT OFFICE.

CHARLES E. STONE, OF BOSTON, MASSACHUSETTS.

PENCIL-SHARPENER.

1,341,943.

Specification of Letters Patent. Patented June 1, 1920.

Application filed August 13, 1919. Serial No. 317,149.

To all whom it may concern:

Be it known that I, CHARLES E. STONE, a citizen of the United States, residing at Boston, in the county of Suffolk and State of

5 Massachusetts, have invented certain new and useful Improvements in Pencil-Sharpener, of which the following is a specification, reference being had to the accompanying drawings.

10 This invention relates to improved pencil sharpeners, and one of the objects of the invention is to provide a simple, efficient and practical device of this kind, which can be manufactured at a relatively low cost and 15 sold at a reasonable profit.

It is well understood that pencil sharpeners of various characters have been heretofore produced and in most of them the holder for the pencil is rotated at the same 20 time the grinding member is operated, and since the lead in the pencil is very often eccentric to the outer surface of the wood, the wood will be ground away unevenly with relation to the lead.

25 Therefore, it is the aim of the present invention to provide a pencil sharpener including a standard on which a rotating member is mounted, and which member carries an abrading or grinding element, in 30 combination with a holder, so positioned relatively to the grinding element, that the pencil may be held at an angle to the element, and by rotating the pencil independently of the holder, the wood around the 35 lead may be ground away evenly.

While the design and construction at present illustrated and set forth is deemed preferable, it is obvious that as a result of a reduction of the invention to a more practical form for commercial purposes, the invention may be susceptible to changes, and the right to these changes is claimed, provided they are comprehended within the scope of what is claimed.

40 The invention comprises further features and combination of parts, as will be herein-after set forth, shown in the drawings and claimed.

In the drawings:

50 Figure 1 is a view in perspective of an improved pencil sharpener constructed in accordance with the invention.

Fig. 2 is a view in elevation showing the side of the pencil sharpener opposite to that 55 shown in Fig. 1.

Fig. 3 is a vertical sectional view on line 3—3 of Fig. 2.

Fig. 4 is a detailed perspective view of the receptacle detached.

Fig. 5 is a detailed view of the grinding 60 or abrading element detached from the rotating member.

Fig. 6 is a detail plan view of the pencil sharpener showing the rotating member and illustrating the pencil holder disposed at an 65 acute angle to the abrading face of the rotating member, whereby a pencil may be held correspondingly.

Referring to the drawings, 1 designates a suitable base, which may be fastened by 70 screws or the like 2 to any suitable stationary support, such as that shown, and rising upwardly from the base is a standard 3. The upper part of the standard has a disk or circular shaped portion 4, which is provided with a screw-threaded socket 5. The upper extremity of the standard terminates in a tubular holder 6, which is open at both ends. The base, the standard and its disk or circular shaped portion, and the tubular 75 holder may be made in a single casting, though not necessarily, for it is obvious that they can be otherwise constructed.

A headed journal pin 7 is threaded into the threaded socket 5, and rotatably supported on its cylindrical part 8 adjacent the head of the pin is the hub portion 9 of the rotating member 10. This rotating member 10 is in the form of a concavo-convex disk, hence it is provided with an annular flange 90 11, which is provided with an annular shoulder 12. It is to be noted that the convex face of the disk or rotating member is substantially flat near its center, and this surface extends radially for a considerable distance, then the surface annularly curves or bevels off toward the flange. A grinding element 13, preferably a piece of sand or emery paper, though not necessarily, is applied to the convex face of the disk for 100 grinding points upon pencils. A disk 14 is arranged upon the journal pin between the grinding element and the disk shaped portion of the standard and is provided with diametrically opposite pins 15. These pins 105 penetrate through openings 16 of the grinding element and into the openings 17 of the rotating member or disk, so that the disk, which is between the standard and the grinding element, may be rotated with the 110

rotating member. This grinding element is substantially circular shaped, and adjacent its marginal edge, it is provided with segmental cut away portions 18, and the parts 19 between the cut away portions 18 are bent over and in contact with the outer face of the flange of the rotating member. A suitable brass, steel, or other metal ring 20 of suitable diameter and any suitable thickness is forced over the grinding element, keeping the portions 19 between the cut away portions flat against the flange of the rotating member. This ring 20 is slipped far enough on the flange of the rotating member to contact with the annular shoulder, thereby preventing movement of the ring in one direction. Since the sand or emery surface of the grinding element faces outwardly, the ring binds sufficiently therewith to prevent its movement in the opposite direction. A suitable handle 21 is swiveled on the journal pin 22, which is carried by the rotating member or disk, so that revoluble movement may be imparted to 25 said member.

A sleeve 23 is fitted telescopically in the tubular holder 6, and is adapted to receive a pencil such as indicated at 24, whereby a point may be ground on one end thereof. 30 This sleeve 23 is provided with a plurality of longitudinally diametrically opposite slits 25 and 26 at its opposite ends, which cause pluralities of spring tongues 27 and 28 to be formed at the opposite ends of the sleeve. By 35 virtue of these spring tongues frictionally engaging with the pencil 24, the pencil is held in position. However, it is not held so firmly that it cannot be turned by hand, for it is the aim that the pencil should be 40 manipulated revolubly as the grinding element rotates, so that the point of the pencil may be ground evenly throughout its length. The cylindrical tubular holder at the upper end of the standard is angular with relation 45 to the standard and disposed at an acute angle to the grinding surface of the grinding element, so as to hold the pencil at an acute angle to such surface, so as to form a tapered point on the end of the pencil. Furthermore, 50 the tubular holder at the upper end of the standard is inclined slightly downwardly in order to facilitate the cutting away of the pencil since the rotating member moves in the direction indicated by the arrow *a* in 55 Fig. 1.

A receptacle 29, which is in the form of a single casting, is secured by means of a screw 30 to the standard. This receptacle is preferably semi-circular in form, though 60 not necessarily, and is secured to the standard concentrically with the rotating member. The wall 31 of the receptacle is provided with a semi-circular cut away portion 32 to receive the spacing disk between the 65 grinding element and the disk of the stand-

ard. A portion of the upper edge of the wall 31 on one side of the cut-away portion 32 is outwardly flared as shown at 33, acting as deflectors, for the purpose of deflecting the dirt or grindings from the pencil into the receptacle. The other wall of the receptacle is likewise cut away in semi-circular form as indicated at 34, but considerably more than the first cut away portion of the wall 31, thereby affording space in which 75 the handle of the rotating member may freely move, when imparting movement to the member.

The circular wear plate 14, preferably, though not necessarily, has the two pins 15 formed integrally therewith, and these pins 15, as previously stated, penetrate through the openings 17 of the rotating member or disk, so that the wear plate may rotate with the disk or member, and also hold the grinding element or sand paper in place. In fact, the pins 15 are designed to be cast solid on the wear plate.

It will be noted that the holder is on the standard to so receive the pencil and hold it 90 at an angle to the grinding or abrading surface that the pencil may be turned around at will, so that the wood of the pencil may be ground away evenly with relation to the lead regardless of whether the lead is eccentric or concentric relative to the wood. Also, the pencil may be moved longitudinally through the holder, so as to grind a point of any suitable length. Furthermore, suitable means have been afforded to secure the 95 abrading or grinding element to the rotating element or disk, consisting of the notches adjacent the edge of the element, so that it may be folded over the marginal periphery of the rotating member, in combination with 100 a ring which is slipped over the grinding element to clamp it in place. Furthermore, by means of the disk 14, the grinding element is held spaced from the standard, so as to prevent injury of the same by contact 105 with the standard. Moreover, the receptacle is constructed in such wise and secured to the standard relative to the rotating member, as to receive the dust and dirt, which results in sharpening pencils with a grinder 110 of this character. It will be noted that owing to the receptacle being cut away, and its particular construction and the manner of applying it to the standard, permits the rotating member to be easily detached from 115 the standard, and the abrading or grinding element removed, without disturbing the receptacle. Furthermore, the cut-away portion of the receptacle allows free movement 120 of the handle of the rotatable member.

The invention having been set forth, what is claimed as new and useful is:

In a pencil sharpener, the combination with a standard having a supporting base at its lower end, its upper end being pro- 130

vided with a detachable journal pin, of a circular rotatable member rotatably mounted upon said pin, an abrading element on the face of the member adjacent the standard, a disk plate having lateral pins passing through the element and into the member and being mounted upon the pin, thereby holding the central part of the abrading element closely in contact with the member and spacing the abrading element from the standard, the upper end of the standard car-

rying a holder at an acute angle to the abrading element and adapted to adjustably slidably receive a pencil to be sharpened, and a receptacle secured to the standard having one wall between the standard and the abrading element, and its other wall cut away to permit movement of a handle on the rotating member.

In testimony whereof I hereunto affix my signature.

CHARLES E. STONE.
